UNITED STATES PATENT OFFICE.

JOHN C. BUMP, OF MILWAUKEE, WISCONSIN, ASSIGNOR TO THE ECLIPSE STOVE COMPANY, OF MANSFIELD, OHIO.

DESIGN FOR A STOVE-BASE.

SPECIFICATION forming part of Design No. 26,006, dated September 8, 1896.

Application filed July 10, 1896. Serial No. 598,755. Term of patent 14 years.

To all whom it may concern:

Be it known that I, JOHN C. BUMP, a citizen of the United States, residing at Milwaukee, in the county of Milwaukee and State of Wisconsin, have invented and produced a new and original Design for Stove-Bases, of which the following is a specification, reference being had to the accompanying drawings, showing the parts thereof.

10 Figure 1 is a plan view of my design for a stove-base. Fig. 2 is a front elevation of the same. Fig. 3 is a vertical transverse section. Fig. 4 is a rear elevation. Fig. 5 is a side elevation of a form of the stove-base, showing an ornamental side panel extending around the stove-base.

My design consists of a cast stove-base having a central depression or ash-pit A, open at the front and closed at the rear and sides. 20 The ash-pit is inclosed on three sides by a flue B of the design and form shown in the accompanying drawings. This flue opens at the front on either side of the ash-pit at C and at the rear in an elongated opening D. The 25 stove-base is provided with openings E E at the rear. The front of the ash-pit is adapted

to be closed by a door. The sides of the stove-base G are of the curved inclined form illustrated. In the form shown in Fig. 5 these sides G are provided with an ornamental conventional design H.

This design comprises a series of conical stems from which infoliated designs spring oppositely, forming between these oppositely-branching leaves plain surfaces which are not 35 ornamented.

The leading features of my design consist of the general shape of the stove-base and also of the ornamentation described upon the side and edge panels.

40 What I claim as new, and desire to secure by Letters Patent, is—

1. The design for a stove-base substantially as shown and described.
2. The design for a stove-base having the 45 ornamentation shown and described.

In testimony whereof I affix my name this 7th day of July, 1896.

J. C. BUMP.
